Don Langsam

INVENTOR.
Carl E. Wolfermann

UNITED STATES PATENT OFFICE.

CARL E. WOLFERMANN, OF NEW YORK, N. Y.

COLLAPSIBLE VEHICLE TOP.

Application filed November 30, 1923. Serial No. 677,701.

This invention relates to folding tops for vehicles and has for its object to provide a top of the so-called extension type, which may be raised or lowered without great effort. The top shows a special advantage in so far that it follows in its width that of the body, for the front section is narrower than the rear section. Another great advantage is claimed for the top because its main bow is thrown ahead by its supplemental member to the edge of the rear door of the body, thereby requiring only a comparatively small number of windows, or curtains, to close the car entirely. An automobile body equipped with this type of top can be used in all weathers, in winter as well as in summer. The windows can be arranged either to drop into the sides of the body or can be taken out when not desired. The top can be folded or raised as desired; a car provided with the same will in appearance look like an open touring car with the top folded or like a closed cabriolet with the top extended.

Other objects and advantages will herein after be referred to and more specifically pointed out in the claims.

The annexed drawings and the following specification set forth in detail a preferred form of a certain mechanism embodying the invention; I am aware that variations of some details of construction may be resorted to without changing the principle of construction and operation of my collapsible vehicle top, and therefore I do not restrict myself further than the scope of the appended claims demands.

In explanation of the drawings I wish to state that the arrangement of all parts of the top is the same on either side, and as the drawings show only a view of one side of the same, I shall refer in the further description only to the location on this one side.

In explanation of the drawings I wish to state:

Fig. 1 is a sectional view of the construction supporting the top mounted on a vehicle body of conventional forms; the dashed lines 26 showing the top in its folded position;

Fig. 2 is a section on lines *a—a* of Fig. 1 showing on a slightly enlarged scale the connecting point of the main bow with the supplemental front bow and brace.

As shown in the accompanying drawing the middle bow 1 has a supplemental part 2,

which parts are hingedly connected with each other at 3; the rear end of said supplemental member is hingedly connected to the body 5 at the main pivot or top support 4. This arrangement allows the middle bow to be in a vertical position at or near the door edge of the body, and when folded to clear the extreme rear of the body by a swinging movement of its supplemental member 2 around pivot 4.

A rear bow 6 is hingedly connected to the main pivot 4, a brace 10 hingedly connected to said rear bow 6 above pivot 4, engages the vertical member of the middle bow 1, hingedly at 11 and insures the vertical position of the upper member of middle bow 1. Brace 10 extends further beyond point 11 and is hingedly connected at its upper end to link 12, which in turn is pivotally connected with the front member of bow 14 at 19, holding the whole structure as a rigid unit when extended.

The front bow 14 has also a supplemental member 13, the latter is pivotally connected to the main bow 1 at 11.

A cover 20 and a back curtain 25 cover and support the whole structure, and when the top is fastened to the windshield 21, bows 14, 1 and 6 are held in a vise like grip.

In order to prevent the top cover 20 from sagging, two auxiliary bows 8 and 15 are inserted, bow 8 being pivotally connected to brace 10 at 7 and bow 15 being jointly connected to link 12 at 16. Bows 8 and 15 may be held by loops formed by strips of leather secured to the top, or by any other means known to the art.

To prevent auxiliary bow 15 from sagging, a stop 17 has been attached to link 12.

To fold the top I release the top from windshield 21 and lift the outer end of the bow 14. This movement will turn bow 14 around pivot 19, thereby breaking joint 18 in a downward direction. At the same time pivot 27 will move toward main bow 1, hereby swinging brace 10 towards and into parallelism with the rear bow 6. This manipulation will lift and draw bow 1 back, to a position as shown in dashed lines 26, Figure 1.

The top is raised by lifting the front bow 14, the rest of the structure will follow easily and take the position, as shown in Fig. 1 when extended, owing to the combination of

the joint arrangement of brace 10 and link 12 with bows 1, 6 and 14 and their respective supplemental members 2 and 13.

What I claim is:—

- 5 1. In a vehicle top of the character described, the combination comprising a middle bow having a vertical member and a horizontal member, the horizontal member being hingedly connected at one end to the lower end of the vertical member, the other end of the horizontal member being hingedly connected to the body, a rear bow hingedly connected to the body at the hinge-point of aforesaid horizontal member, a brace hingedly connected to the rear bow above this point and to the upper portion of the vertical member of the middle bow, a front bow, comprising a front member and a rear member, hinged to the vertical member, a connecting link hingedly connected to the front member of the front bow and to the upper end of the brace.
- 10 2. In a vehicle top of the character described, the combination comprising a middle bow consisting of a vertical member and a horizontal member, the horizontal member being hingedly connected at one end to the lower end of the vertical member and at its other end to the vehicle body, a rear bow hingedly connected to the body at the same pivot as the aforesaid horizontal member, a brace hingedly secured at its upper end to the vertical member of the middle bow and
- 15
- 20
- 25
- 30

at its lower end to the rear bow, and a front bow hingedly secured to the aforesaid vertical member at the same pivot where the brace is hingedly connected and being supported by a link which is hingedly connected at one end to said front bow and at the other end to the upper end of aforesaid brace.

3. In a vehicle top of the character described, the combination comprising a middle bow consisting of a vertical member and a horizontal member, the horizontal member being hingedly connected at one end to the lower end of the vertical member and at its other end to the vehicle body, a rear bow hingedly connected to the body at the same point as the aforesaid horizontal member, a brace hingedly secured at its upper end to the vertical member of the middle bow and at its lower end to the rear bow, a front bow hingedly secured to the aforesaid vertical member at the same pivot where the brace is hingedly connected and being supported by a link hingedly connected at one end to said front bow and at the other end to the upper end of aforesaid brace, an auxiliary bow hingedly connected to aforesaid brace, and an auxiliary bow hingedly connected to aforesaid connecting link and limited in its forward movement by a stop.

In testimony whereof I affix my signature.

CARL E. WOLFERMANN.
